ADJUSTABLE BOBBIN TRUCK

Noah W. Eurey, Lincolnton, N.C., assignor, by mesne assignments, to Excel, Inc., Lincolnton, N.C., a corporation of North Carolina

Application January 21, 1955, Serial No. 483,227

3 Claims. (Cl. 280—79.2)

This invention relates to hand trucks and more especially to bobbin trucks of the type used in textile mills for transporting bobbins and the like from one operation in the mill to another.

Heretofore, hand trucks have been manufactured which have had cargo bins that were adjustable vertically as well as being adjustable as to horizontal angularity so as to render the articles within the bin more accessible by depositing them in the lowered end of the bin. However, in each case the horizontal angularity has been adjustable by some type of manually operable adjustment so that once the truck bin is adjusted vertically a separate manual adjustment is required each time it is desired to change the horizontal angularity of the bin of the bobbin truck. This is a decided disadvantage since such adjustments are necessarily time consuming and must frequently be made within the narrow space provided by the alleys between textile machines and the like.

It is therefore a primary object of this invention to provide a bobbin truck, the bin-holding frame of which is vertically adjustable and also resiliently mounted on the upper end of the vertically adjustable support means whereby the horizontal angularity of the bin may be adjusted by exerting downward pressure on either end of the bin-holding frame to thus make the bobbins carried by the bin slide or move by gravity to the lowered end thereof so that the weight thereof will maintain the bin at a desired angle to render the bobbins easily accessible to the operator. If an operator desires to remove bobbins from the opposite end of the bin of the truck without turning the truck around he may exert downward pressure on the opposite end of the bin to remove bobbins therefrom.

It is another object of this invention to provide means for vertically adjusting the height of the bin-holding frame of a bobbin truck which may be quickly and easily operated to allow the height of the bin-holding frame to be quickly adjusted.

Some of the objects of the invention having been stated, other objects will appear as the description proceeds when taken in connection with the accompanying drawings, in which—

Figure 1 is a side elevation of the improved bobbin truck;

Figure 2 is an end view of the improved bobbin truck looking at the left-hand end of Figure 1;

Figure 3 is a sectional plan view taken substantially along line 3—3 in Figure 1;

Figure 4 is an enlarged vertical sectional view taken substantially along line 4—4 in Figure 3;

Figure 5 is a fragmentary vertical sectional view taken substantially along line 5—5 in Figure 4.

Referring more specifically to the drawings, it will be observed that the bobbin truck includes a base portion broadly designated at 10, comprising an oblong continuous bumper or outer frame member 11, a longitudinally extending support member 12 suitably secured at opposite ends to the elongated continuous bumper 11 and transversely extending support members 13, 13a, 14, 15, 16 and

2

16a. The support members 14, 15 are suitably secured at their opposite ends to the oblong continuous bumper 11 (Figure 3) and the transverse frame members 13, 13a, 16 and 16a are secured, at opposite ends, to the bumper 11 and the support member 12. Wheels 20 are journaled in suitable supports 21 fixedly secured adjacent opposite ends of the transverse frame members 14 and 15, and end wheels 23 are journaled in suitable supports 24 fixed to opposite ends of the longitudinally extending frame member 12. It will be noted by referring to Figures 1 and 2, that the lower peripheries of the wheels 20 are at a lower elevation than the end wheels 23 so as to facilitate manipulation of the bobbin truck.

The longitudinally extending frame member 12 has fixedly secured thereto the lower end of a vertically disposed rectangular tubular guide or support member 30 which is additionally supported by suitable angularly disposed bracing members 31 and 32 which extend between the guide member 30 and the frame member 12.

The support member 30 has an opening 35 cut therein adjacent the upper end thereof which is provided to accommodate an eccentric cam wheel 36 fixed to the horizontal portion 37 of an operating lever 40. The horizontal portion 37 of the lever arm 40 is rotatably or oscillatably mounted in a pair of support arms 41 and 42 secured to opposite side edges of the guide member 30.

The eccentric cam wheel 36 is adapted to, at times, engage and clamp vertically movable slide bar 45 which is slidably mounted for vertical movement inside the support member 30. The medial portion of a transversely extending plate or angle bracket 46 is secured to the upper end of the slide bar 45, opposite ends of the transversely extending angle bracket 46 being provided with respective lower spring anchoring elements 50 and 50' (Figures 2, 3 and 5) fixedly secured thereto. The brackets 50 and 50' are adapted to hold and support the corresponding ends of a pair of closely wound coil springs 51, 52 and 51', 52', respectively, the other ends of the springs 51, 52 and 51', 52' being supported by upper spring anchoring elements 55, 55'. The brackets 55, 55' are suitably secured to respective longitudinally extending bin-holding frame members 56 and 57, corresponding ends of which are joined together by curved end plate members 60 and 61.

An upper elongated continuous band 63 is spaced above the longitudinally extending frame members 56 and 57 and suitably supported in spaced relationship thereabove by outwardly diverging frame members 64, 65, 66 and 67, which extend between respective longitudinal frame members 56 and 57 and the continuous band 63. The continuous oblong band member 63 supported above the longitudinally extending frame members 56 and 57 provides an open framework for the insertion of a conventional bobbin bin 70 shown in dash-dot lines in Figures 1 and 2.

55 The lower spring holding and support brackets 50 and 50' have one end of respective chains 71 and 72 secured thereto, the opposite ends of which are fixed to the respective frame members 56 and 57. The chains 71, 72 are safety chains to prevent over-exertion or over-loading of either of the coil springs 51, 52, 51' and 52' as either end of the bobbin bin 70 is lowered. The longitudinally extending frame members 56 and 57 are also provided with downwardly extending plate members 74 and 74' adjacent the central portion thereof which serve to protect the respective springs 51, 52 and 51', 52', and to prevent any foreign objects such as a bobbin or the like from becoming lodged therebetween.

To adjust the vertical height of the bobbin bin 70 the lever 40 may be moved in a counterclockwise direction in Figures 1 and 2 to move the periphery of the cam wheel 36 out of engagement with the slide 45 in the guide member 30 to thus allow the slide 45 to be raised or low-

ered relative to the guide member 30 and thus raise or lower the bobbin bin 70 to a convenient height. Upon the proper level being determined by the operator, the handle or lever 40 may then be moved in a clockwise direction to substantially the position shown in Figures 1 and 2 so that the inner periphery of the cam wheel 36 will engage the slide 45 to thus wedge the slide 45 against the opposite side of the guide 30 and to thus clampingly engage and hold the slide 45 at the desired elevation in the guide 30.

As shown in Figure 5, the lower spring anchoring brackets 50, 50' and the upper spring anchoring brackets 55, 55' are connected only to the outer portions of their respective pairs of springs 51, 52 and 51', 52', the inner portions of said springs being unsupported. As previously noted, the springs are closely wound so that the outer portions of the coils of the springs bear against each other when subjected to the weight of the bin carrier, as clearly shown in Figure 5. Consequently, the contacting outer portions of the springs confined between the brackets 50, 55 and 50', 55' limit transverse tilting of the bin carrier while permitting the bin carrier to be tilted longitudinally.

The bobbin bin 70 may be horizontally adjusted or lowered at either end by an operator by merely pushing down on either end of the bobbin bin 70 to extend either pair of the springs 51, 51' or 52, 52' to thus lower either end of the bobbin bin 70, as desired. If there are a sufficient number of bobbins in the bobbin bin 70 the bobbin bin 70 will remain lower at the end to which the bobbins have slid and as the bobbins in the lowered end are removed therefrom the stretched spring will tend to collapse or close the coils thereof to again return the bobbin bin 70 to substantially a horizontal position.

It is thus seen that I have provided a bobbin truck provided with a bin which is quickly and positively vertically adjustable as well as being resiliently and pivotally mounted for the easy and quick lowering of either end of the bin.

In the drawings and specification there has been set forth a preferred embodiment of the invention and although specific terms are employed, they are used in a generic and descriptive sense only and not for purposes of limitation, the scope of the invention being defined in the claims.

I claim:

1. In a truck having a wheeled base and a tiltable bin carrier the combination of means for supporting said bin carrier in variable spaced relation above said base and for resiliently maintaining said bin carrier in a substantially horizontal position; said supporting means comprising a tubular guide fixedly secured to said wheeled base, a slide member the lower end of which is slidably mounted in said guide member and an eccentric cam wheel mounted on said tubular guide and engageable with said slide member for preventing relative sliding movement between said slide member and said guide member, said resilient maintaining means comprising a transverse plate on the upper end of said slide member, first and second pairs of longitudinally spaced closely wound coil springs extending between said transverse plate and said bin carrier, said second pair of springs being spaced transversely from said first pair of springs, upper and lower spring anchoring elements secured to the bin carrier and the transverse plate respectively, and said spring anchoring elements each being connected to the outer portions of one pair of springs in such a manner as to normally maintain the bin

carrier in a horizontal attitude and to permit longitudinal tilting of the bin carrier in response to the application of a force or load to either end of the bin carrier while limiting transverse movement of the bin carrier.

- 5 2. In a truck having a wheeled base, a tiltable bin carrier and support means extending upwardly from the medial portion of said base for maintaining said bin carrier in vertical spaced relation to said base, the combination of means for resiliently connecting said bin carrier to said support, said connection means comprising a transverse plate secured to the upper end of said support, first and second vertically spaced spring anchoring elements disposed at opposite sides of said support, said first spring anchoring elements being connected to said transverse plate adjacent opposite ends thereof and said second spring anchoring elements being connected to said bin carrier, a pair of longitudinally spaced closely wound coil springs adjacent each end of the transverse plate, each pair of springs extending between said vertically spaced spring anchoring elements, the distal portions of each pair of springs relative to the other pair of springs being secured between their respective vertically spaced spring anchoring elements, said springs normally urging said bin carrier to a substantially horizontal attitude and being yieldable under pressure applied vertically to either end of said bin carrier to permit said bin carrier to tilt longitudinally relative to said wheeled base, and limiting means extending between said bin carrier and said transverse plate for limiting longitudinal tilting movement of said bin carrier beyond a predetermined point.
- 10 3. In a load carrying device comprising a base and a load carrying surface arranged above the base, means resiliently supporting the load carrying surface above the base for tiltable movement through a predetermined vertical plane while otherwise limiting the load carrying surface against tiltable movement relative to the base, said means comprising first and second vertically spaced spring anchoring elements disposed adjacent opposite sides of the base, said first spring anchoring elements extending in parallel relation to said vertical plane and being connected to the base adjacent opposite sides thereof and said second spring anchoring elements being connected to the load supporting surface in coinciding relation to the first spring anchoring elements, a pair of closely wound coil springs adjacent each side of the base, the springs in each pair of springs being spaced from each other in a direction parallel to said vertical plane and extending between said vertically spaced spring anchoring elements, and the outer portions of each pair of springs being secured to their respective vertically spaced spring anchoring elements whereby said load carrying surface is normally urged to a substantially horizontal attitude and limited against movement transversely of said vertical plane.
- 15 4. In a load carrying device comprising a base and a load carrying surface arranged above the base, means resiliently supporting the load carrying surface above the base for tiltable movement through a predetermined vertical plane while otherwise limiting the load carrying surface against tiltable movement relative to the base, said means comprising first and second vertically spaced spring anchoring elements disposed adjacent opposite sides of the base, said first spring anchoring elements extending in parallel relation to said vertical plane and being connected to the base adjacent opposite sides thereof and said second spring anchoring elements being connected to the load supporting surface in coinciding relation to the first spring anchoring elements, a pair of closely wound coil springs adjacent each side of the base, the springs in each pair of springs being spaced from each other in a direction parallel to said vertical plane and extending between said vertically spaced spring anchoring elements, and the outer portions of each pair of springs being secured to their respective vertically spaced spring anchoring elements whereby said load carrying surface is normally urged to a substantially horizontal attitude and limited against movement transversely of said vertical plane.
- 20 5. In a load carrying device comprising a base and a load carrying surface arranged above the base, means resiliently supporting the load carrying surface above the base for tiltable movement through a predetermined vertical plane while otherwise limiting the load carrying surface against tiltable movement relative to the base, said means comprising first and second vertically spaced spring anchoring elements disposed adjacent opposite sides of the base, said first spring anchoring elements extending in parallel relation to said vertical plane and being connected to the base adjacent opposite sides thereof and said second spring anchoring elements being connected to the load supporting surface in coinciding relation to the first spring anchoring elements, a pair of closely wound coil springs adjacent each side of the base, the springs in each pair of springs being spaced from each other in a direction parallel to said vertical plane and extending between said vertically spaced spring anchoring elements, and the outer portions of each pair of springs being secured to their respective vertically spaced spring anchoring elements whereby said load carrying surface is normally urged to a substantially horizontal attitude and limited against movement transversely of said vertical plane.
- 25 6. In a load carrying device comprising a base and a load carrying surface arranged above the base, means resiliently supporting the load carrying surface above the base for tiltable movement through a predetermined vertical plane while otherwise limiting the load carrying surface against tiltable movement relative to the base, said means comprising first and second vertically spaced spring anchoring elements disposed adjacent opposite sides of the base, said first spring anchoring elements extending in parallel relation to said vertical plane and being connected to the base adjacent opposite sides thereof and said second spring anchoring elements being connected to the load supporting surface in coinciding relation to the first spring anchoring elements, a pair of closely wound coil springs adjacent each side of the base, the springs in each pair of springs being spaced from each other in a direction parallel to said vertical plane and extending between said vertically spaced spring anchoring elements, and the outer portions of each pair of springs being secured to their respective vertically spaced spring anchoring elements whereby said load carrying surface is normally urged to a substantially horizontal attitude and limited against movement transversely of said vertical plane.
- 30 7. In a load carrying device comprising a base and a load carrying surface arranged above the base, means resiliently supporting the load carrying surface above the base for tiltable movement through a predetermined vertical plane while otherwise limiting the load carrying surface against tiltable movement relative to the base, said means comprising first and second vertically spaced spring anchoring elements disposed adjacent opposite sides of the base, said first spring anchoring elements extending in parallel relation to said vertical plane and being connected to the base adjacent opposite sides thereof and said second spring anchoring elements being connected to the load supporting surface in coinciding relation to the first spring anchoring elements, a pair of closely wound coil springs adjacent each side of the base, the springs in each pair of springs being spaced from each other in a direction parallel to said vertical plane and extending between said vertically spaced spring anchoring elements, and the outer portions of each pair of springs being secured to their respective vertically spaced spring anchoring elements whereby said load carrying surface is normally urged to a substantially horizontal attitude and limited against movement transversely of said vertical plane.
- 35 8. In a load carrying device comprising a base and a load carrying surface arranged above the base, means resiliently supporting the load carrying surface above the base for tiltable movement through a predetermined vertical plane while otherwise limiting the load carrying surface against tiltable movement relative to the base, said means comprising first and second vertically spaced spring anchoring elements disposed adjacent opposite sides of the base, said first spring anchoring elements extending in parallel relation to said vertical plane and being connected to the base adjacent opposite sides thereof and said second spring anchoring elements being connected to the load supporting surface in coinciding relation to the first spring anchoring elements, a pair of closely wound coil springs adjacent each side of the base, the springs in each pair of springs being spaced from each other in a direction parallel to said vertical plane and extending between said vertically spaced spring anchoring elements, and the outer portions of each pair of springs being secured to their respective vertically spaced spring anchoring elements whereby said load carrying surface is normally urged to a substantially horizontal attitude and limited against movement transversely of said vertical plane.
- 40 9. In a load carrying device comprising a base and a load carrying surface arranged above the base, means resiliently supporting the load carrying surface above the base for tiltable movement through a predetermined vertical plane while otherwise limiting the load carrying surface against tiltable movement relative to the base, said means comprising first and second vertically spaced spring anchoring elements disposed adjacent opposite sides of the base, said first spring anchoring elements extending in parallel relation to said vertical plane and being connected to the base adjacent opposite sides thereof and said second spring anchoring elements being connected to the load supporting surface in coinciding relation to the first spring anchoring elements, a pair of closely wound coil springs adjacent each side of the base, the springs in each pair of springs being spaced from each other in a direction parallel to said vertical plane and extending between said vertically spaced spring anchoring elements, and the outer portions of each pair of springs being secured to their respective vertically spaced spring anchoring elements whereby said load carrying surface is normally urged to a substantially horizontal attitude and limited against movement transversely of said vertical plane.
- 45 10. In a load carrying device comprising a base and a load carrying surface arranged above the base, means resiliently supporting the load carrying surface above the base for tiltable movement through a predetermined vertical plane while otherwise limiting the load carrying surface against tiltable movement relative to the base, said means comprising first and second vertically spaced spring anchoring elements disposed adjacent opposite sides of the base, said first spring anchoring elements extending in parallel relation to said vertical plane and being connected to the base adjacent opposite sides thereof and said second spring anchoring elements being connected to the load supporting surface in coinciding relation to the first spring anchoring elements, a pair of closely wound coil springs adjacent each side of the base, the springs in each pair of springs being spaced from each other in a direction parallel to said vertical plane and extending between said vertically spaced spring anchoring elements, and the outer portions of each pair of springs being secured to their respective vertically spaced spring anchoring elements whereby said load carrying surface is normally urged to a substantially horizontal attitude and limited against movement transversely of said vertical plane.
- 50 11. In a load carrying device comprising a base and a load carrying surface arranged above the base, means resiliently supporting the load carrying surface above the base for tiltable movement through a predetermined vertical plane while otherwise limiting the load carrying surface against tiltable movement relative to the base, said means comprising first and second vertically spaced spring anchoring elements disposed adjacent opposite sides of the base, said first spring anchoring elements extending in parallel relation to said vertical plane and being connected to the base adjacent opposite sides thereof and said second spring anchoring elements being connected to the load supporting surface in coinciding relation to the first spring anchoring elements, a pair of closely wound coil springs adjacent each side of the base, the springs in each pair of springs being spaced from each other in a direction parallel to said vertical plane and extending between said vertically spaced spring anchoring elements, and the outer portions of each pair of springs being secured to their respective vertically spaced spring anchoring elements whereby said load carrying surface is normally urged to a substantially horizontal attitude and limited against movement transversely of said vertical plane.
- 55 12. In a load carrying device comprising a base and a load carrying surface arranged above the base, means resiliently supporting the load carrying surface above the base for tiltable movement through a predetermined vertical plane while otherwise limiting the load carrying surface against tiltable movement relative to the base, said means comprising first and second vertically spaced spring anchoring elements disposed adjacent opposite sides of the base, said first spring anchoring elements extending in parallel relation to said vertical plane and being connected to the base adjacent opposite sides thereof and said second spring anchoring elements being connected to the load supporting surface in coinciding relation to the first spring anchoring elements, a pair of closely wound coil springs adjacent each side of the base, the springs in each pair of springs being spaced from each other in a direction parallel to said vertical plane and extending between said vertically spaced spring anchoring elements, and the outer portions of each pair of springs being secured to their respective vertically spaced spring anchoring elements whereby said load carrying surface is normally urged to a substantially horizontal attitude and limited against movement transversely of said vertical plane.
